ALF HJORT, OF NEW YORK, N. Y., ASSIGNOR OF ONE-FOURTH TO HENRY JAPP, OF NEW YORK, N. Y.

TELEGRAPH.

1,163,539.

Specification of Letters Patent.

Patented Dec. 7, 1915.

Application filed April 1, 1912. Serial No. 687,701.

To all whom it may concern:

Be it known that I, ALF HJORT, a subject of the King of Norway, and residing in the city, county, and State of New York, have invented a certain new and useful Improvement in Telegraphs, of which the following is a specification.

My invention relates to telegraphs and the object of my invention is to provide a telegraph system and apparatus in which an alternating current may be successfully employed.

My invention contemplates the transmission of alternating currents of predetermined frequency to a receiving appliance which comprises vibrators tuned to respond to the varying frequencies of the currents transmitted and preferably adapted to automatically effect the record of a corresponding series of symbols or letters.

In the accompanying drawing my invention is illustrated in a diagrammatic embodiment thereof in one form.

The basis of the present system is the discovery that a reed of steel or other suitable material having a certain predetermined frequency of vibration may be set in motion by subjecting it to the influence of an alternating current of coinciding frequency.

Briefly, the transmitting apparatus consists of a source of alternating electric current, the frequency of which can be selected at will. The receiving apparatus consists of a coil through which the alternating currents are passed, and supported within the coil a series of steel vibrators or reeds of predetermined various frequencies. When a current of selected frequency is passed through the coil from the transmitter, the reed of corresponding frequency will be set in motion. This vibration of the reeds may be utilized to effect the record of different symbols, for example a different letter of the alphabet for each reed, so that the messages may be thus transmitted and recorded.

In the particular form diagrammatically shown in the drawing, the transmitter comprises a constant speed motor 10 which drives a series of alternating current generators—A to I, of small size and uniform make, but each at a different speed from the other. The speeds of these generators are so regulated and positively determined through a proper regulation of the gears

11, 12 by which they are connected to the main driving shaft 13, that each generator has a predetermined frequency. One terminal 14 of each generator may be connected to the line wire 15 or grounded. The other terminals 17 of the generators may be connected to switch keys A¹ to I¹, one for each generator, (and preferably comprising the keyboard of a typewriter) so that upon the depression of any one of the keys A¹ to I¹ the line circuit is closed through that particular generator, by reason of its engagement with one of the various terminals 18 for the line wire 16. It is thus obvious that a series of currents of different frequencies may be passed over the line wires by the temporary closing of the various switches A¹ to I¹ in the order desired.

The receiving apparatus as illustrated comprises a receiving coil 19 connected to the line wires 15, 16, or the connection to line 15 grounded. Longitudinally within the coil are arranged a series of reeds 20^a, 20^b, 20^c corresponding in number to the number of generators and each having a frequency of vibration tuned to the frequency of the particular generator to which it is intended to respond. So that for example the completion of the circuit from the particular generator A through the coil 19, by the depression of a particular key A¹ causes the corresponding reed 20^a to vibrate at the receiving apparatus. The reeds may be carried by brackets 21 in which they are adjustably secured by clamping screws 22, so that they may be accurately tuned to the desired frequency.

The record effected by the vibration of the reed may be secured in any desired way. An arrangement is shown in connection with reed 20^a for automatically effecting the actuation of typewriter keys. To this end, an auxiliary circuit is used which may be derived from any suitable source 23. Two electro-magnets 24 and 25 are arranged in this circuit the one (24) positioned above a lever 26 attached to a typewriter key lever 27, and the other (25) positioned above one end of a damping lever 28. The circuit is normally broken between a contact 29 and the end of reed 20^a through which the circuit is passed. When, for instance, the circuit from generator A is passed through the coil 19 by the depression of key A¹, the reed 20^a which is tuned to the frequency of this generator, 110

vibrates. This vibration closes the auxiliary circuit through the contact 29 thereby energizing the electro-magnet 24. This rocks the lever 26 on its pivot 30 and de-
5 presses the key lever 27 thus printing the letter *a* of the typewriter. The small magnet 25 is simultaneously energized, with the result that the damping lever 28 is attracted and rocked on its pivot whereby the end
10 overlying the reed 20^a is momentarily pressed down upon the latter to check its vibration and prevent repeated contact with the terminal 29. This particular arrangement is merely illustrative of an automatic
15 recording device operated by the vibration of the rods 20^a, etc., and is by no means to be regarded as the only arrangement contemplated by me.

In transmitting messages over long dis-
20 tances, the current passing between the transmitter and receiver may be stepped up to a high voltage by stationary transformers in a manner well understood by those skilled in the art and stepped down again
25 at the receiving end, thus saving in the weight of long distance transmission lines.

If it is desired to send more than one message over the line at once, it is only necessary to build the transmitters and re-
30 ceivers with different ranges of frequency. Thus one set of transmitters and receivers could make use of frequencies varying from
20 to 40 cycles; the next set could use frequencies ranging from 50 to 70 cycles; while
35 a third set could use frequencies ranging from 80 to 100 cycles; and so on. These subdivisions are only given to indicate how the different sets could be tuned, but the

range can be reduced or lengthened as may be found advisable.

I claim as my invention:—

1. A telegraph system comprising a group of alternating current generators of various predetermined frequencies, and selective means for energizing the line circuit therefrom, in combination with a receiving coil in the line circuit and a group of vibrators arranged within magnetic field of said coil and variously tuned to the frequencies of said generators.

2. A telegraph system comprising a group of alternating current generators of various predetermined frequencies, and selective means for energizing the line circuit therefrom, in combination with a corresponding group of vibrators variously tuned to the frequencies of said generators and means for subjecting said vibrators to the influence of the currents of various frequencies transmitted over said line circuit from the generators, together with an auxiliary circuit for each vibrator, a recording device for each vibrator and controlled by said auxiliary circuit, and means in connection with the motion of said vibrator for operatively closing said auxiliary circuit, together with means for damping the motion of said vibrator after the auxiliary circuit has been closed.

In testimony whereof I have signed my name to this specification, in the presence of two subscribing witnesses.

ALF HJORT.
